The Schedule referred to, in these Letters Patent and making part of the same

~~~~~*

To all to whom these presents shall come

Be it known, that we A Cox, Elias Johnson, & D B Cox of Troy in the County of Rensselaer and State of New York have invented or produced a new and original design for cooking stoves, and that the following is a full, clear, and exact description of the principle or character which distinguishes it from all other things before known reference being had to the accompanying drawing, which forms a part thereof.

This design is illustrated in Figs 1 & 2. Fig 1 is a side elevation. Fig 2 a front elevation showing one of the doors only; on the side is an oven door (a) the front edge of which is of an ogee form, the corners being rounded and the lower portion being extended under the fire door and open under the chamber. This door is ornamented with a broad beaded moulding all around its edge within which are rays projecting from a scroll work door at the center. The side fire door (b) in the upper front corner of the side plate is square and ornamented similarly to the oven door above des-

Ms. 383

773

erected over the oven door is a legend of date of patent &c and at the bottom of the Stove is an ornamental border consisting of elemental foliage - a small diamond ornament is introduced in the lower front corner above the foliated border. Fig 0 shows the front, the sunk hearth is very deep and of an ogee form - at its sides but otherwise plain - the front doors two in number are ornamented by a center figure consisting of sprays radiating from a center ornament like the side door

Having thus fully described our improved design what we claim and desire to secure by letters Patent is the pattern described and illustrated of ornamental design stone pattern
